UNITED STATES PATENT OFFICE

100,377

DESIGN FOR A SHEAR

Alden A. Lincoln, Fairfield, Conn., assignor to
The Acme Shear Company, Bridgeport, Conn.,
a corporation of Connecticut

Application January 16, 1936, Serial No. 60,620

Term of patent 3½ years

To all whom it may concern:

Be it known that I, Alden A. Lincoln, a citizen of the United States, residing at Fairfield, county of Fairfield, State of Connecticut, have invented a new, original, and ornamental Design for a Shear, of which the following is a specification, reference being had to the accompanying drawing, forming part thereof.

Fig. 1 is a plan view of shear, showing my new design; and

Fig. 2 is an edge view thereof looking from the top of Fig. 1.

The dominant feature of my design resides in the gradual inclination of the offset pivot portion of the blade shanks that merges into flowing corresponding curves of the adjacent handles. This feature, combined with the straight cutting blades, produces a pleasing stream line effect for the shear.

I claim:

The ornamental design for a shear, substantially as shown and described.

ALDEN A. LINCOLN.
